J. H. WHIPPLE.

HOOD.

No. 17,247.

Patented Apr. 5, 1887.

Fig. 1.

Fig. 2.

UNITED STATES PATENT OFFICE.

JOSEPH H. WHIPPLE, OF BATTLE CREEK, MICHIGAN.

DESIGN FOR A HOOD.

SPECIFICATION forming part of Design No. 17,247, dated April 5, 1887.

Application filed November 17, 1886. Serial No. 219,216. Term of patent 3½ years.

To all whom it may concern:

Be it known that I, JOSEPH H. WHIPPLE, a citizen of the United States, residing at Battle Creek, in the county of Calhoun and State of Michigan, have invented and produced a new and original Design for Hoods; and I do declare the following to be a full, clear, and exact description of the same, reference being had to the accompanying photographic representation, forming a part thereof.

The features of this design in knithoods consist in the ornamentation thereof.

The design is illustrated in the accompanying photographic representation, in which—
15 Figure 1 is a front and Fig. 2 a side view of the hood.

In shape the hood is at least as high as its width at the base. The hood is also longer in the back than in the front. The base of the 20 hood has an upturned or folded plait, A, of substantially the proportional width shown. This plait is wider in the front than in the rear. The hood curves uniformly from the base convergingly to the apex of the hood. At 25 the apex is a small ball or pompon, B. On the

front the hood is ornamented with two large pompons, C C, placed side by side. A bow, D, is arranged between them, and also two small suspended balls or pompons, E E. Bands F F are arranged at the sides and slightly in the 30 rear.

I claim as my invention—

1. In a design for a hood, the herein-described ornamentation, consisting of the large balls or pompons C C and the small balls E E between the large balls or pompons, substantially as shown and described.
2. In a design for a hood, the upturned plait A, the large balls or pompons C C, the small balls E E between the large balls, the bow 40 D above the small balls and between the large ones, the small ball B at the apex of the hood, and the ribbons F F, substantially as shown and described.

In testimony whereof I affix my signature in presence of two witnesses.

JOSEPH H. WHIPPLE.

Witnesses:

STEVEN S. HULBERT,
F. R. MECHEM.
